GAMEBOARD TABLE

Mancel F. Guthrie, 1810 Eye St., Bakersfield, Calif.

Filed Aug. 31, 1964, Ser. No. 81,506

Term of patent 7 years

(Cl. D34—5)

FIG. 1 is a perspective view of the gameboard table showing my new design.

FIG. 2 is a reduced scale top plan view of the gameboard of FIG. 1.

FIG. 3 is a bottom plan view of the gameboard of FIG. 2.

FIG. 4 is a view in side elevation of the gameboard of FIG. 2.

I claim:

The ornamental design for a gameboard table, as shown.
